RAIL AND FLANGE LUBRICATOR

Edmond Ivan Hetsch, Valley Stream, N. Y.

Application February 23, 1938, Serial No. 191,931

10 Claims. (Cl. 184—3)

This invention relates to improvements in automatically operative rail and flange lubricators adapted for applying lubricant to reduce the resistance and rail and wheel flange wear incident to the passage of railway rolling stock around curves in the track structure. An object of the present improvements is to provide a lubricator adapted for successfully lubricating with grease as the lubricant and to more fully meet the exacting requirements of track maintenance and with greater efficiency of lubrication than has heretofore been accomplished.

Important advantages and features of my improved device comprise an improved arrangement of supply tank and grease pump designed for positioning beneath the rail for actuating the pump responsive to wave movement of the rail and wherein the pump is structurally a self contained and readily removable or replaceable unit and is of an improved positive, rectilinear acting plunger type providing for an augmented movement of the pump plunger in its action; and in operative association therewith an improved depressible and rockable distributor member of an improved design adapted to effect, in co-operation with the wheels, a progressive and uniform depositing of the grease on the flange contact surface of the rail.

The aforementioned and other valuable features and advantages of the present improvements will be more fully understood by reference to the accompanying drawings wherein like reference characters are applied to the corresponding parts in the several views.

35 In the drawings:

Fig. 1 is a plan view illustrating my improved lubricating device or mechanism as assembled with relation to the rail to be lubricated.

Fig. 2 is a view thereof in side elevation.

40 Fig. 3 is a partial sectional view of the tank showing the pumping mechanism assembled therewith and in central, vertical section.

Fig. 4 is a detail, vertical sectional view showing the rail engaging actuator portion and taken at right angles to Fig. 3.

Fig. 5 is a horizontal, sectional view taken on line 5—5 of Fig. 3.

Fig. 6 is a similar view taken on line 6—6 of Fig. 3.

50 Fig. 7 is a partial cross-sectional view of the rail and distributor blade portion taken on line 7—7 of Fig. 2.

Fig. 8 is a detail, vertical sectional view through the distributor showing the adjustable features thereof.

In the approved embodiment of the features of my invention as here shown the lubricant supply tank is indicated at 1 and is of generally rectangular form and of a size adapting it for positioning between adjacent ties and beneath the rail. The top wall or cover plate of the tank is provided at one end with a filler opening closed by a hinged cover 2 and at the opposite end is formed with an opening 3 therein for the reception of a pumping unit formed at its upper portion with a supporting plate forming a cover for the opening.

In accordance with my invention, the pumping mechanism for the lubricant is formed as a self contained unit adapted for ready removal and replacement and to be actuated by the displacement of the rail under the weight of the rolling stock or wave movement of the rail. The pumping unit comprises a supporting and bearing member or frame 5 formed at its upper end portion with an integral supporting plate 6 forming the cover for the opening 3 and secured in position by screw studs 7.

The supporting member 5 is generally cylindrical and provided with bearings for a vertically movable pump plunger mechanism comprising a lower plunger 8 and upper plunger extension or actuator member 9 in axial alignment therewith and interposed means for transmitting increased movement to the plunger. As shown, 25 the plunger 8 is fitted within a bearing insert member 10 supported by the member 5. The upper end of the plunger is formed with a headed portion 12 beneath which is confined a compression spring 13 bearing upon bearing member 10 30 and acting normally to raise the plunger 8. The lower end of the plunger acts as a piston for forced feed of the lubricant from a cylinder or pump chamber 14 formed within a chamber member 16 formed as an insert to the lower 40 cylindrical portion of the supporting member.

As best shown in Fig. 3, the chamber member is threaded to member 5 at 18 and is formed with an internal thread 19 to receive a bottom closing plug 21 having a squared wrench cavity. In an intermediate plane, the chamber member is formed with an external, annular discharge groove 23 connected by radial openings or bores 24 with the chamber or central bore 14. In position to communicate with the discharge groove 50 23, the bearing member 5 is formed with boss 25 having discharge passage 26, the bore of which is provided with a valve seat 27 for a ball check valve 28 held by spring 29 confined between the ball and a threaded closing plug 30. 55

Outwardly of the valve seat 27, the passage 26 is provided with a lateral discharge port 32 to which is connected a lubricant feed pipe 33 connecting through cover opening 35 and pipe coupling 36 to a distributor member hereinafter described. At 38 is shown a packing washer fitted to a chamber member recess to insure a close seal between the chamber member and the supporting member 5.

10 The pumping motion is transmitted to the pump plunger 8 from the adjustable actuator member 9 fitted to vertically reciprocate in bearing portions 40-41 of the supporting member in axial alignment with the plunger 8. The 15 actuator member, as shown, is provided with an adjustable, externally extending contact member 42 of hardened steel having a rounded head portion 43 positioned to be engaged by the under surface of the rail flange for actuation by the 20 wave motion of the rail. The contact member is threaded to the actuator member at 44 and squared at 45 for vertical adjustment within the actuator and formed with lower extension 46 closely fitting the bore in the actuator which is 25 longitudinally and oppositely slotted at 48 to provide a contractable region about which is fitted a bearing bracket 50 provided with a retaining set screw 52 upon which tightening secures the bracket and clamps the contact member in adjusted position by compression of the slotted portion of the actuator. Surrounding the actuator and bearing against the under surface of bracket 50 and the upper surface of bearing portion 41 of the supporting frame is a compression spring 30 54 imparting upward or lifting pressure upon the actuator. The bracket member 50, as shown, is formed with an extension 56 to which is threaded a vertical adjusting screw 57 bearing against the underside of a stop extension of the bearing portion 40 and provided with a lock nut 58. As the bracket 50 is affixed to and movable with the actuator, this screw by its engagement with the supporting member acts as an adjustable stop to the upward movement of the actuator as is readily understood.

45 The lower end portion of the actuator is connected by means of pivot pin 60 with bearing yoke member 62 which is rockable about the pivot 60 and vertically movable in a vertical slideway formation 63 of the supporting member. The 50 bearing yoke is provided with equi-distantly, oppositely disposed rounded bearing portions 64 positioned to bear upon and depress the pivoted arms 65 inwardly extending from pivotal bearings 66 with their inner headed end portions 67 bearing upon the pump plunger head enlargement 12. The arms or levers 65, as best shown in Fig. 5, are symmetrically formed to engage the plunger head at all times equi-distantly from the central axis thereof and at opposite sides of the axis so as to have a balanced or compensating effect in the transmission of the increment of movement from the actuator to the plunger 8. The slideway formation for the bearing yoke is 55 open sided permitting of the employment of yokes of varied spacing of bearing portions 64 to establish the ratio of plunger movement to that of the actuator 9 as may be desired. The wall of the supporting member is formed with side 60 openings 70 and the bearing insert member 10 at its lower portion is formed with communicating openings permitting entrance of the lubricant into the cylinder 14 beneath the plunger 8 when the latter is elevated.

75 As will be understood, upon positioning of the

tank in the ballast and with the actuator contact head 43 underlying the rail flange, as shown in Figs. 1 and 2, the position of the contact member is adjusted relative to the rail to determine the desired feed or delivery stroke of the pump 5 as related to the given rail section and degree of wave motion thereof. The adjusted position of the contact member is maintained upon tightening of screw 52 and adjusting of set screw 57 will limit the upward movement of the actuator 10 and correspondingly regulate the pumping action or effective pumping stroke with relation to the movement of the rail.

Accordingly, the improved pump structure, in addition to being self contained as a removable 15 unit, is designed to have rectilinear movement of its operating parts with balanced action of its leverage arms with the important advantage that in operation no resultant lateral forces or stresses are transmitted to the container such as would 20 in time tend to disturb the correct relative position of the tank and pump actuator to the rail and the operating adjustment as established. As will be appreciated this contributes materially to the successful operation over long periods of use 25 as required.

Associated with the described pump structure I employ an improved distributor device for more 30 efficiently distributing the lubricant to the wheel flanges and in a manner whereby the wheels in 35 their travel will transfer the lubricant to the flangeway side of the rail head more uniformly and over an extended distance of rail length for more efficient curve lubrication. The improved distributor, or applicator, as shown in Figs. 1, 2 40 and 7, comprises a depressible and rockably supported distributor head member fulcrumed upon bearing pin 81 and having a rearward bored portion 83 connected by a flexible hose 84 to the pump discharge coupling 36 as shown.

The bearing pin 81 is carried by a suitable supporting bracket 86 formed to extend beneath and clamp to the rail base flange *f* of rail *r*, clamping bolt and co-acting clamp 80 being provided therefor. The distributor head is provided with 45 the grease passage 88, as shown, terminating as an upwardly inclined passage having a delivery port positioned centrally in the upper surface of the head member and within a transverse recess 89 thereof formed in the upwardly and forwardly 50 extended blade portion 90 of the distributor head member. The blade portion as illustrated is supported to normally assume a position closely adjacent to the flange side of the rail head with the groove 89 in the position approximately midway 55 of the height of the rail head; the upper or blade portion of the distributor head being formed with its outer side inclining or tapering upwardly with a curvature contour conforming substantially to the inner surface of the wheel 60 flange.

As best shown in Fig. 8, the distributor head is formed with a depending lug 92 engaged at one side by a spring 93 fitted within a socket of the bracket 86 and at the opposite side by an 65 adjustable stop screw 94 threaded in the bracket to adjustably limit the upward swing of the blade portion to determine its normal raised position. This structural arrangement permits of the distributor blade portion depressing when 70 engaged by an exceptionally close or worn wheel flange as a protective and safety factor.

As an additional feature and as best shown in Fig. 8, the mounting of the distributor upon its pivot pin 81 includes an interposed rubber bush- 75

ing 96 which functions to permit a limited degree of lateral tilting or rocking inwardly of the distributor blade upon engagement by the wheel flange. This arrangement allows of normally 5 positioning of the distributor blade for engagement with wheel flanges of average or normal clearance of the rail head or outward position with relation thereto. As a result thereof a very substantial improvement in the distribution of 10 the grease along the rail is obtained. As will be understood, wheel flanges in close proximity or engagement with the rail head will in consequence of such closeness immediately redistribute the grease upon the rail resulting in excessive 15 application of the lubricant over a small area. Application of the grease to the outwardly spaced flanges as effected by my improved arrangement results in carrying forward of the grease over a greatly extended area of rail and primarily by 20 reason of differences of wheel diameters and also varied side play of the successive wheels a relatively uniform film of the lubricant is progressively deposited on the rail for many of the 25 wheel flanges will travel well into the curve before making rail contact. In addition to the improved and progressive distribution of the grease by the wheels as described, the improved form of the distributor blade as shown having its forward extension normally upwardly inclined from 30 the delivery port directs the distribution of the grease to the throat of the engaging wheel flange.

Having described my invention, I claim:

1. A rail and flange lubricating device comprising in combination with the rail, a lubricant supply tank adapted for positioning in the ballast below the rail, a self contained pump unit secured to and extending within the tank, said pump unit having an actuator positioned to be engaged by the rail, a pump plunger adapted to operate in vertical alignment with the actuator, motion transmitting levers engaging the plunger in opposed, balanced relation and a yoke bearing member between the levers and actuator for transmitting increased motion from the actuator to the plunger, a distributor member and connections from the pump to the distributor.

2. A rail and flange lubricating device comprising in combination with the rail, a lubricant supply tank, a self contained pump unit secured to and extending within the tank, said pump unit having an actuator positioned to be engaged by the rail, an adjustable contactor carried by the actuator, a pump plunger supported to operate in vertical alignment with the actuator, oppositely and outwardly pivoted motion transmitting levers engaging the plunger in balanced relation, a yoke bearing member pivotally connected to the actuator and having oppositely spaced bearing portions engaging the levers for transmitting increased motion from the actuator to the plunger, a pump chamber member co-acting with the plunger, means normally operative to elevate the actuator and plunger, a distributor and connections from the pump chamber member to the distributor, substantially as described.

3. A rail and flange lubricating device comprising in combination with the rail, a lubricant supply tank adapted for positioning in the ballast below the rail, a self contained pump unit secured to and extending within the tank, said pump unit having an actuator positioned to be engaged by the rail, adjustable means to limit the movement of the actuator toward the rail, a pump plunger adapted to operate in vertical

alignment with the actuator, motion transmitting levers engaging the plunger in opposed, balanced relation, a yoke bearing member between the levers and actuator, means operative normally to elevate the plunger and actuator, a distributor and connections from the pump to the distributor.

4. A rail and flange lubricating device comprising in combination with the rail, a lubricant supply tank, a self contained pump unit secured to and extending within the tank, said pump unit comprising a supporting and bearing member, an actuator member operating in vertical bearings in the supporting member, a contactor adjustably mounted in the actuator, a stop bracket member slidably fitted on the actuator, a stop screw carried in the bracket to engage the supporting member for limiting the upward movement of the actuator, a retaining screw for securing the bracket on the actuator, a spring positioned normally to elevate the actuator, a pump plunger supported to operate in vertical alignment with the actuator, opposite outwardly pivoted motion transmitting levers engaging the plunger in balanced relation, a yoke bearing member pivotally connected to the actuator and having opposite, spaced bearing portions engaging the levers for transmitting increased motion from the actuator to the plunger, a spring positioned to be operative for normally raising the plunger, a pump chamber member co-acting with the plunger, a distributor and connections from the pump chamber to the distributor, substantially as described.

5. A rail and flange lubricating device comprising in combination with the rail, a lubricant supply tank, a pump unit secured to and extending within the tank, said pump unit comprising a supporting and bearing member, an actuator member operating in vertical bearings in the supporting member, a contactor adjustably mounted in the actuator and having a lower clamping extension, said actuator being slotted in the region of said extension, a stop bracket member slidably fitted on the actuator, a stop screw carried in the bracket to engage the supporting member for adjustably limiting the upward movement of the actuator, a retaining screw for securing the bracket on the actuator and clamping the contactor extension, a pump plunger supported to operate in vertical alignment with the actuator, opposite outwardly pivoted motion transmitting levers engaging the plunger in balanced relation, a yoke bearing member pivotally connected to the actuator and having opposite spaced bearing portions engaging the levers, a spring positioned to be operative normally to raise the plunger, a pump chamber member removably secured to the supporting member in alignment with the plunger, a distributor and connections from the pump chamber to the distributor, substantially as described.

6. A rail and flange lubricator having in combination with the rail and pump mechanism operated responsive to passage of rolling stock over the rail, of a distributor connected to the pump and comprising a supporting bracket and a distributor member carried by the bracket and having a forwardly extending blade portion for engagement with the wheel flanges, said distributor member being mounted upon the bracket whereby the blade portion thereof is depressible in a plane parallel to the rail and rockable in a lateral plane with relation to the rail and means to

limit the upward movement of the blade portion, substantially as described.

7. A rail and flange lubricator having in combination with the rail and pump mechanism operated responsive to passage of the rolling stock over the rail, of a distributor connected to the pump and comprising a supporting bracket secured to the rail, a distributor member, a fulcrum bearing on the bracket for said member, 10 said distributor member having a forwardly extending blade portion provided with a lateral recess in its rearward upper surface and a discharge port communicating with said recess and having its forwardly extended portion upwardly 15 and inwardly inclined to substantially conform to wheel flange contours and said fulcrum bearing including an elastic bushing whereby the blade portion will be compressible by movement on the fulcrum in a vertical plane parallel to the rail and will be laterally rockable in the plane transverse to the rail substantially as described. 20
8. A rail and flange lubricating device comprising in combination with the rail, a lubricant supply tank adapted for positioning in the balance 25 last below the rail, a self contained pump unit secured to and extending within the tank, said pump unit having an actuator positioned to be engaged by the rail, means for adjusting the position of the actuator with relation to the rail, 30 adjustable stop means adapted to limit the upward movement of the actuator, a pump plunger adapted to operate in vertical alignment with the actuator, motion increasing levers pivoted to engage the plunger in opposed balanced relation 35 and a yoke bearing member interposed between the actuator and the levers, a distributor member and a connection from the pump to the distributor member.

9. A rail and flange lubricator having in com-

bination with the rail and pump mechanism operated responsive to passage of rolling stock over the rail, of a distributor connected to the pump and comprising a supporting bracket and a distributor member pivotally carried by the bracket and having a forwardly extending blade portion for engagement with the wheel flanges, said distributor member being movable whereby the blade portion is compressible in a vertical plane parallel to the rail and rockable transversely 10 with relation to the rail, means to limit the upward movement of the blade portion and said blade portion having its flange engaging surface positioned outwardly from the rail a distance sufficient for engagement with wheel 15 flanges relatively widely spaced from rail engagement.

10. A rail and flange lubricator having in combination with the rail and pump mechanism operated responsive to passage of rolling stock over the rail, of a distributor connected to the pump and comprising a supporting bracket and a distributor member pivoted upon the bracket and having a forwardly extending blade portion for engagement with the wheel flanges provided with 25 a recess in its rearward upper surface and a discharge port communicating with said recess, spring means arranged normally to elevate the blade portion, adjustable stop means on the bracket operative to limit the upward movement 30 of the blade portion, an elastic bushing interposed between the pivot and the distributor to permit lateral rocking of the distributor member and said blade portion having its flange engaging surface positioned outwardly from the rail a distance sufficient for engagement with wheel 35 flanges relatively widely spaced from the rail.

EDMOND IVAN HETSCH.
